[57] CLAIM

The ornamental design for a stake, as shown and described.

DESCRIPTION

FIG. 1 is a front elevational view of a stake showing my new design, the rear view being identical.

FIG. 2 is a side elevational view thereof, the opposite side being identical.

FIG. 3 is a cross-sectional view taken on line 3—3 of FIG. 1.

FIG. 4 is a perspective view thereof.

FIG. 5 is a bottom plan view thereof.

FIG. 6 is a cross-sectional view taken on lines 6—6 of FIG. 1.

FIG. 7 is a top plan view.

FIG. 7
